[57] ABSTRACT

A lottery apparatus comprises a closed container in which a roll of continuous strip of tickets numbered in a random disorder is completely enclosed. Means are provided in the container for the withdrawal of the strip from the container through an outlet opening thereof and for preventing the strip when withdrawn to be returned to the container. The container prevents reading of the number of a ticket until it is completely withdrawn from the container.

LOTTERY APPARATUS

In such lotteries where the drawing is made before the lottery-tickets are sold it is, of course, an indispensable requirement that nobody can read the numbers of the lottery-tickets without first breaking a seal which cannot be re-established, in order that the persons handling the distribution and sale of the lottery-tickets will not be able imperceptibly to separate winning lottery-tickets from other tickets. Different types of rolled and folded lottery-tickets have been proposed in order to satisfy this requirement.

The present invention provides a new solution to the problem of maintaining the number secrecy in lotteries of the type referred to above until the lottery-ticket has been sold, which differs from the principles hitherto adopted by the fact that the tickets are sealed not individually but collectively, whereby the seal may be provided in a simpler but nevertheless more reliable manner than that adopted for rolled and folded tickets. At the same time it is easier to distribute the tickets and to check the sale thereof.

According to the invention this is achieved by a lottery apparatus comprising numbered tickets which are provided as a roll of a continuous strip on which the successive tickets are numbered in a non-regular sequence and from which the tickets can be separated individually, characterized in that the strip having the numbers visibly printed on the individual tickets thereof for the protection of the number secrecy is enclosed in a container which forms an opening for the withdrawal of the tickets and which prevents the ticket number of each ticket to be read until the ticket is substantially completely withdrawn from the container, and further characterized in that means are provided to prevent a partially withdrawn ticket from being returned to the container.

In order to automatize a lottery apparatus of the type referred to such that the withdrawal of the ticket is achieved due to the fact that one or more coins are introduced into a coin slot of a prepayment mechanism, the lottery apparatus is further characterized in that a knob is provided on the container for the withdrawal of the tickets, and that the container is replaceably mounted having the knob releasably connected with a turning member which may be connected with a manual operating mechanism by driving means which is to be activated by one or more coins supplied to the prepayment mechanism.

The lottery apparatus according to the invention will now be described with reference to the accompanying drawings, in which

FIG. 1 discloses the container and the ticket strip, parts of the container being broken away to show the interior of the container;

FIG. 2 is a perspective view of the container disclosed in FIG. 1;

FIG. 3 is a fragmentary plan view of the ticket strip;

FIG. 4 is a perspective view of a lottery-ticket vending machine having two lottery apparatuses according to the invention mounted therein;

FIG. 5 is a perspective view of an operating mechanism in the lottery apparatus a blocking mechanism included therein being shown in an inoperative position;

FIG. 6 is a view corresponding to FIG. 5 and showing the blocking mechanism in the position wherein a ticket has been withdrawn but has not been separated from the strip;

5 FIG. 7 is a view corresponding to FIG. 5 showing the blocking mechanism in the position at the separation of a ticket;

FIG. 8 is a diagrammatic side view of the lottery apparatus in an inoperative position;

10 FIG. 9 is a detail view of the lottery apparatus taken according to line IX — IX in FIG. 8;

FIG. 10 is a view corresponding to FIG. 8 disclosing essential parts of the mechanism shown therein when a coin has been introduced into the prepayment mechanism;

FIG. 11 is a view corresponding to FIG. 8 but disclosing the elements in the position when a ticket is being withdrawn;

20 FIG. 12 is a detail view, substantially in vertical section of a portion of the housing of the lottery-ticket vending machine according to FIG. 4;

FIG. 13 is a diagrammatic view of a sensing means in the position when there is a ticket strip in the lottery apparatus; and

25 FIG. 14 is a view corresponding to FIG. 13 in the position when there is no ticket strip in the lottery apparatus.

The lottery-ticket vending machine disclosed in the drawings comprises a container 10 e.g. of plastics, including two identical half portions each forming an end wall 11 and a side wall 12. One or both of the container half portions is formed or provided with tongues or other projections (not shown) on the inner surface of the side wall, projecting from the side wall at the edge thereof to guidingly engage the other container half portion inwardly of the side wall thereof when the two half portions are put together. The portions may be welded or glued together or mechanical fasteners may be provided for this purpose. On the container half portions there may be provided fittings or lugs for the attachment of sealing members such as a seal wire and lead so that the interior of the container when the two half portions are interconnected is not available from the outside without breaking the seal. In the container there is provided on the end wall of each half portion a central cylindrical pin 13 for rotatably mounting a roll 14 of a paper strip or tape 14'. The container forms in one of the end walls thereof a bearing for a wheel 15 provided with drive dogs 16 arranged to engage holes formed in the strip as will be described below, for withdrawal of the strip from roll 14 by rotation of the wheel in a counter-clockwise direction as seen in FIG. 1. Wheel 15 forms saw teeth 17 at the periphery thereof such teeth cooperating with a spring blade ratchet 18 mounted in the container, to prevent the wheel from being rotated in the direction opposite to that in which the wheel has to be rotated in order to withdraw the strip from the container. Thus, the strip when once withdrawn cannot be returned to the container. Between wheel 15 and a partition 19 provided in the container there is formed a passage for the strip such partition preventing the strip from disengaging drive dogs 16. The passage leads to an outlet opening 20 in the side wall of the container at the lower side thereof.

The strip forming roll 14 consists of a number of integral lottery-tickets 21 adapted to be separated from each other along lines 22 according to a uniform pitch.

On each ticket there is printed a ticket number at 23, text naming the organization arranging the lottery and giving other useful information at 24, and a number identifying the roll, which is the same on all tickets of the roll, at 25. The tickets are not numbered in order but in a random disorder such that it is not possible to determine the number of a following ticket by guidance of the number of a ticket just withdrawn from the container. Of course, this possibility has to be completely eliminated as far as lotteries are concerned wherein the drawing has been made before the sale of the tickets. In the ticket strip there are punched circular holes 26 for the engagement of wheel 15 at drive dogs 16 the circumferential pitch of such dogs corresponding to the pitch of the holes of the ticket strip.

Due to ratchet means 17, 18 a ticket which has been withdrawn from the container sufficiently for the ticket number to be read therefrom, cannot be returned to the container when it has been determined that the ticket withdrawn is no winning ticket. This prevents criminal handling of the tickets by returning non-winning tickets to the container. It will be seen that the successive tickets of the rolled strip, numbered in a non-regular sequence, is safely enclosed in the container when this has been sealed the ticket numbers being protected against unauthorized inspection, and that the tickets one at a time or several at a time may be withdrawn from the container no possibility being given to push the strip back into the container when the ticket number or numbers on the portion of the strip withdrawn from the container have been read. Thus, the ticket numbers are kept secret until the tickets are withdrawn and this is an indispensable requirement as far as lotteries of the type referred to are concerned.

The lottery apparatus described is extremely well suited for safety measures which have to be taken in lotteries, and for the distribution and sale of the tickets.

For the withdrawal of tickets from container 10 this will be combined with a coin controlled operating mechanism which will now be described with reference to FIGS. 4 - 14 in the drawings. The operating mechanism may be common for two or more containers a prepayment mechanism being provided for each container such that the ticket strip of the container or containers in the prepayment mechanism of which a coin has been introduced, will be withdrawn and delivered when the operating mechanism is manually operated. In the embodiment shown two containers 10 are presumed to be arranged in a housing 27 an operating handle 28 being located on the right side of this housing as seen in FIG. 4. The housing is supported at the lower part thereof on a base 28, and a frame for mounting the containers and the other parts and elements of the lottery apparatus is mounted on this base the frame being fragmentarily indicated by dot and dash lines 30 in the several figures. Base 29 receives a coin collecting drawer 29' wherein coins passing through the prepayment mechanism are collected. This drawer has to be provided with a lock.

Each container 10 may be removably connected with the frame by known means such as clamp springs which mount the container in a fixed position in the frame with wheel 15 coupled to a turning member which comprises a hollow stub shaft 32 rotatably mounted on a stationary pin 31 said shaft being notched at the free end thereof to engage a knob 33 (FIG. 2) provided on

wheel 15 and projecting from container 10 on the outer side thereof. On pin 31 which is supported by frame 30 there is provided a drive means 34 comprising a gear wheel 35 rotatably mounted on shaft 32, a spring biased drive pawl 36 pivoted to gear wheel 35, and an engagement disk 37 non-rotatably connected with shaft 32 coaxially therewith close to gear wheel 35. Disk 37 is formed with two notches 38, pawl 36 being arranged to engage these notches one at each time. It is biased towards such engagement by a spring 36'. However, a back holder 39 pivoted on a pin 39' is provided to be kept by a catch 40 in a position wherein back holder 39 keeps pawl 36 in a passive position, against a bias provided by a counterweight 41 at one end of back holder 39. Catch 40 is pivoted on a pin 40' supported by frame 30 and is biased by a coiled tension spring 40'' anchored in frame 30 to engage a notch 39'' in back holder 39. It will be actuated to release the back holder 39 by a coin supplied to a prepayment mechanism 42.

A shaft 43 extending in parallel to stub shaft 32 carries a tooth sector 44 non-rotatably connected with said shaft and engaging gear wheel 35. Shaft 43 may be actuated by operating handle 28 over a gearing comprising a gear wheel 45 non-rotatably connected with shaft 43 and engaging a tooth sector 46 which is in turn non-rotatably connected with a shaft 47 parallel to shaft 43 and supporting operating handle 28. The pivoting movement of the operating handle is limited by abutments, not shown, to an angular range providing a rotation of gear wheel 35 of a half revolution, and the operating handle may be spring biased to a rest position at one end of this angular range. Furthermore, there is provided on shaft 43 a cam member 48 for providing a return movement of back holder 39 for re-engagement with catch 40. Shafts 43 and 47 are rotatably mounted by bearings, not shown, which are mounted by frame 30 in a conventional manner.

The lottery apparatus also comprises a cutter 49, 50 disposed in the output path of the ticket strip delivered through opening 20 of container 10. This cutter which comprises a stationary blade 49 supported by the frame and a movable blade 50 pivoted to the frame is actuated by operating handle 28 by means of an arm 51 mounted on shaft 43 and arranged to actuate movable blade 50 to sever a ticket from the strip against stationary blade 49.

The prepayment mechanism 42 included into the apparatus may be of a conventional type and, therefore, it is not disclosed in detail. However, it comprises a coin passage which is indicated by dash and dot lines 52. An arm 53 connected with catch 40 at one end thereof projects into this passage.

Before the further details of the operating mechanism are described the operation of the operating mechanism as described so far will be explained.

FIG. 8 shows the operating mechanism in an initial position. Operating handle 28 is in its rest position in which notches 38 are in the positions seen in FIG. 8, i.e. one notch is disposed on top of disk 37 and the other one at the bottom of the disk. Catch 40 is in the blocking position thereof engaging notch 39'' in the upper end of back holder 39. Pawl 36 engages back holder 39 under the bias of spring 36' which means that when gear wheel 34 is rotated by operating handle 28 pawl 36 will clear the adjacent notch 38 and will not contact disk 37 until it has passed this notch. Then the pawl will

slide along the cylindrical surface of the disk without driving this disk by the rotation of gear wheel 34.

FIG. 10 shows the elements of the operating mechanism when a coin has been introduced into the prepayment mechanism 42 and has passed through coin passage 52. For the introduction of the coin into the prepayment mechanism there is provided in housing 27 a coin slot 54, one for each mechanism, since two containers and an associated prepayment mechanism for each container are provided in the lottery apparatus described. When passing through passage 52 the coin will actuate catch 40 at arm 53 projecting into the passage. When the coin contacts this arm catch 40 will be pivoted in a clockwise direction as seen in FIG. 10 about pin 40' thereof and will release back holder 39 which will be rotated in a clockwise direction as seen in FIG. 10 to move from pawl 36 under the bias provided by counterweight 41. Thus, the pawl will be rotated to the activation position thereof under the bias provided by spring 36', this position being shown in FIG. 10, and will engage the top notch 38 in disk 37. When operating handle 28 is now moved to the right as seen in FIG. 5 in order to withdraw a ticket 21 completely from the container without separating the ticket from the strip at cutter 49, 50 the condition disclosed in FIG. 11 will be attained.

During this movement of operating handle 28 shaft 43 and thus arm 51, tooth sector 44 and cam member 48 will be rotated in a clockwise direction as seen in FIGS. 8 and 11. This means that arm 51 will move towards the movable blade 50 of the cutter. Tooth sector 44 will rotate gear wheel 35 in a clockwise direction as seen in FIG. 5 - 7 and in a counter-clockwise direction as seen in FIGS. 8 and 11. When gear wheel 35 is rotated, pawl 36 engaging disk 37 will be moved in the same direction and, thus, stub shaft 32 engaging knob 33 of container 10, will be actuated to rotate the knob in order to withdraw ticket 21 from the container. When shaft 43 is rotated in a clockwise direction as seen in FIGS. 8 and 11, cam member 48 will be rotated in the same direction and will actuate the lower portion of back holder 39 which will be returned to its initial position wherein catch 40 engages the back holder. When shaft 43 is rotated a coin passage blocking member 55 forming part of the prepayment mechanism will be actuated by a pin, not shown, on pawl 36 in order to be moved into passage 52 and prevent a further coin inserted through the coin slot from passing through the prepayment mechanism before a ticket has been withdrawn and cut off from the strip due to the activation of the operating mechanism brought about by the proceeding coin. When operating handle 28 is further actuated after withdrawal of the ticket the movable blade 50 will be actuated by arm 51 on shaft 43 so that cutter 49, 50 will sever the ticket; cf. FIG. 7. When operating handle 28 is returned or returns to the initial position thereof, i.e. the rest position, all the elements included in the operating mechanism will be returned to their initial positions and the lottery apparatus is now prepared for a new operation when a coin has been supplied to the prepayment mechanism and has passed through the coin passage thereof.

If a ticket is withdrawn from the container but is not separated from the ticket strip there may be the risk that there will be delivered from the machine several integral tickets of a sufficient length to allow the strip to be gripped manually and be withdrawn from the con-

tainer although a number of coins corresponding to the number of tickets withdrawn have not been supplied to the prepayment mechanism. A blocking mechanism preventing this procedure is disclosed in FIGS. 5 - 7 and comprises a blocking arm 56 which is connected with shaft 43 at one end thereof to be rotatable together with said shaft and which has at the free end thereof a notch 57. Below shaft 43 there is disposed a blocking latch 58 pivoted to a pin 59 which projects from frame 30 the fulcrum of said blocking latch being located in such manner that the blocking latch will be held by its own weight in a substantially vertical position one end of the latch being directed upwardly in such position. This end is bevelled to form a sharp edge 60. On frame 30 close to blocking latch 58 there is provided an abutment pin 61 preventing the blocking latch to be rotated a complete revolution.

In FIG. 5 the blocking mechanism is shown in a non-operative condition wherein blocking arm 56 and blocking latch 58 are disengaged so that operating handle 28 may be unobstructedly operated for rotating shaft 43 in a counterclockwise direction as seen in FIG. 5 such rotation of the shaft being necessary for the withdrawal of a ticket when a coin has been supplied to the prepayment mechanism as described above. In FIG. 6 the movement of operating handle 28 has continued for the withdrawal of a ticket from the container in the manner described but not to a degree sufficient for severing the ticket from the strip. It will be seen that shaft 43 has been rotated over gearing 45, 46 to bring arm 51 into contact with the movable blade 50 of cutter 49, 50 without actuating said blade. During the rotation of shaft 43 blocking arm 56 pushing away end 60 of blocking latch 58 engages this end at notch 57. If the operator in this position tries to return operating handle 28 to the initial position thereof this will be prevented by the engagement between blocking arm 56 and blocking latch 58 such engagement preventing shaft 43 to be rotated in a clockwise direction as seen in FIG. 6. However, the actuation of the handle may continue, and by this continued movement of the operating handle and the elements related thereto blade 50 will be moved against blade 49 to cut off the ticket from the strip as seen in FIG. 7. During this operation blocking arm 56 will swing past blocking latch 58 which will be pushed away by the blocking arm and eventually will be free from this arm to swing back to the initial position behind the blocking arm by its own weight. Now, when the operating handle is returned blocking arm 56 will push away blocking latch 58 at the bevelled end without engaging the latch and the blocking mechanism will retain its initial non-operative position. A further operation for withdrawing a ticket may now be initiated when a coin or coins have been supplied to the prepayment mechanism.

In the lottery-ticket vending machine according to FIG. 4 there is provided in housing 27 for each lottery apparatus an outlet opening 27' for the separated tickets behind a canopy 62 a channelled receptacle 63 for collecting the tickets being arranged in connection with the outlet opening. Canopy 62 comprises a strip formed of a blade 64 which is fitted to the outer surface of housing 27. This strip is bent to extend from the housing substantially in parallel to the bottom of receptacle 63 between the side walls thereof and then in parallel to the front wall of the housing to a lower level into the receptacle the strip terminating close to the bottom of

the receptacle leaving a space between the end of the strip and the bottom. This form of canopy 62 makes it impossible to reach the lottery-ticket before an individual ticket which has been withdrawn from the container has been cut off by cutter 49, 50 when the ticket is in the position according to FIG. 6. In this position the ticket is located behind canopy 62 where it cannot be reached from the outside. When the ticket has been severed from the ticket strip and falls down into receptacle 63 it may be removed from the machine.

In FIGS. 13 and 14 there is disclosed a stop mechanism comprising a resiliently supported sensing member 65 abutting the edge of ticket strip 14' under the action of a spring bias. This member is mounted for linear displacement towards and away from the ticket strip edge by a sub-frame 66 mounted on frame 30 and is held back against the spring bias when there is a ticket strip in the path of the strip. It is operatively connected with a two-armed pivoted lever 67 which is held in the position according to FIG. 13, a passive position, when member 65 is in the position according to FIG. 13. However, the lever is insertable into coin passage 52 to prevent a coin from passing fully through this passage. In this position the lever forms a deflector which will deflect the coin into a return passage in a manner known in the art. In housing 27 there is provided a coin slot 68, FIG. 4, through which the returned coin will be recovered.

Housing 27 may be provided with directions for the use of the lottery-ticket vending machine and with indicating means for indicating that the apparatus has failed or that the tickets are sold out.

What we claim is:

1. A lottery apparatus for dispensing individual numbered tickets from a roll of tickets, the apparatus comprising:

a frame;

a closed container having a single outlet opening, the container being replacably mounted as a separate unit in the frame;

a roll of a continuous strip forming successive tickets numbered in a non-regular sequence, the roll being enclosed in the container for the protection of the roll's number secrecy;

rotative means on the closed container communicating with the interior of the container for effecting the withdrawal of the strip from the container through the outlet opening;

means enclosed by the container for preventing the withdrawn strip from being returned to the container; and,

driving means carried on the frame for releasably engaging the rotative means when the container is mounted in the frame whereby activation of the driving means causes withdrawal of the strip from the container through the outlet opening.

2. A lottery apparatus as claimed in claim 1 further comprising a manual operating mechanism and a prepayment mechanism for activating the driving means by at least one coin supplied to the prepayment mechanism.

3. A lottery apparatus as claimed in claim 2 wherein the driving means comprises a stub shaft formed for en-

gagement with the rotative means, and a pivoted member which is movable back and forth about the stub shaft by means of the operating mechanism and is provided with an engagement operable from an inoperative position to an operative position by means of the prepayment mechanism, said engagement member engaging the stub shaft in the operative position to carry it along in the movement of the pivoted member.

4. A lottery apparatus as claimed in claim 3 wherein

10 the engagement member comprises a pawl which is biased towards an engaged position, and wherein the prepayment mechanism includes a pivoted back holder for holding the pawl in a disengaged position against the bias.

15 5. A lottery apparatus as claimed in claim 4 further comprising a catch for the back holder operatively connected with the prepayment mechanism to hold the back holder in a position, in which the pawl is disengaged, and to release the back holder in dependence of the prepayment mechanism, and means for returning the back holder to an operative position by means of the operating mechanism.

20 6. A lottery apparatus as claimed in claim 2 further comprising a cutter for severing a ticket from the withdrawn strip, the cutter being activated by the operating mechanism at continued operation thereof after the withdrawal of the strip, and the operating mechanism being operatively connected with a blocking means preventing the return movement of the operating mechanism before the cutter has been operated.

25 7. A lottery apparatus comprising:

a frame;

a container enclosing a roll of continuous strips and provided with an outlet opening, the container being replacably mounted in the frame;

rotative means within the container including means for allowing only the withdrawal of the strips from the container through the outlet opening;

driving means, including a stub shaft, carried on the frame and releasably connected to the rotative means;

a manual operating mechanism driving the stub shaft, said manual operating mechanism including a pivoted member moveable back and forth about the stub shaft;

a pawl mounted on the pivoted member and biased towards and engaged position on the stub to carry said stub shaft along with the movement of the pivoted member; and

a prepayment mechanism including a pivoted back holder for holding the pawl in a disengaged position and means for releasing the back holder.

30 8. A lottery apparatus as claimed in claim 7 in which said means for releasing the back holder comprises a catch for the back holder operatively connected with the prepayment mechanism to hold the back holder in a position in which the pawl is disengaged, and to release the back holder in dependence on the prepayment mechanism, and means for returning the back holder to an operative position by means of the operating mechanism.
